UNITED STATES PATENT OFFICE.

ERNEST T. HALEY, OF LUFKIN, TEXAS.

FIREPLACE-GUARD.

1,273,776.

Specification of Letters Patent. Patented July 23, 1918.

Application filed April 25, 1917. Serial No. 164,509.

To all whom it may concern:

Be it known that I, ERNEST T. HALEY, a citizen of the United States, residing at Lufkin, in the county of Angelina and State 5 of Texas, have invented certain useful Improvements in Fireplace-Guards, of which the following is a specification, reference being had therein to the accompanying drawing.

10 This invention has reference generally to fireplace attachments and more particularly relates to a fireplace guard.

As the primary aim and object the present invention resides in the provision of 15 novel guarding means adjustably mounted on the columns of a fireplace and adapted to be removably extended so as to rest on the hearth to prevent pieces of burning or hot fuel from rolling from the hearth upon the 20 adjacent floor, thereby preventing the occurrence of accidental fires.

It is an additional and equally important object of the present invention to provide 25 means for adjustably connecting the sections of the guarding means so that the guarding means may be applied to fireplaces having various sized openings and to also provide means for adjustably connecting the guarding means to the columns so that the guarding 30 means may be extended or reduced so as to readily fit upon hearths of various sizes.

As a further improvement, the present invention embraces the provision of novel 35 means carried by the lintel of the fireplace for removably retaining the guarding means in an inoperative position when it is not desired to use the same.

A more specific object of the present invention consists in the provision of novel 40 attaching plates for supporting and guiding the guarding means.

Among the other aims and objects of the present invention may be recited the provision 45 of a device of the character mentioned with a view to compactness, and in which the number of parts are few, the construction simple, the cost of production low and the efficiency high.

50 Other objects as well as the nature, characteristic features and scope of this invention will be more readily apparent from the following description taken in connection with the accompanying drawings, and 55 pointed out in the claims forming a part of this specification.

The preferred embodiment of the inven-

tion is clearly illustrated in the accompanying drawings, in which:—

Figure 1 is a perspective view of the device arranged in an operative position on a fireplace.

Fig. 2 is a front elevation of the same showing the guarding means in an inoperative position.

Fig. 3 is a sectional detail of one of the attaching plates.

Similar characters of reference are employed in all of the above described views, to indicate corresponding parts.

Referring now, more particularly, to the accompanying drawings there is illustrated a fireplace including a hearth 1, and spaced side columns 2 connected at the outer ends by a lintel 3. This fireplace of course may 75 be of any conventional construction as it forms no important part of the invention, being simply illustrated in order that a thoroughly comprehensive understanding of the invention may be obtained.

With a view toward providing the improved guarding means in the present instance there is employed a substantially U-shaped guard member composed of two preferably right angled sections 4 formed of any suitable metal. The outer end of each section is provided with a longitudinal series of openings 5 any one of which is engaged by a suitable fastening device such as a screw 6 through the instrumentality of 90 which the sections are adjustably connected in order that the guard member may be applied to fireplaces having openings of various widths. The inner end of each member is also provided with a longitudinal series of openings 7 for facilitating the adjustable connection of the guard member in order that it may be accommodated on hearths of various depths.

In order to adjustably connect the guard member to the fireplace a pair of attaching plates 8 are employed. Each of these plates has its lower end bent at a right angle to provide anchoring portions 9 which are engaged beneath the side columns 2 in such a 105 manner that the plates lie against the opposed faces of the side columns as indicated in the drawing. The upper end of the plates is provided with a short longitudinal slot 10 which serves as a means for facilitating 110 the anchoring of a suitable fastening device 11 in the mortar between adjacent bricks, the head of the fastening device being arranged flush with the outer face of the plate,

Each of these plates 8 is further provided with an elongated longitudinal slot 12 while the inner face of the plate is provided about the slot with a longitudinal groove 13 which 5 forms a shoulder 14 for a purpose that will presently appear. Headed bolts 14' are passed through the slots from the inner faces preparatory to the mounting of the plates, and also engaged in one of the openings 7 10 in the inner end of the angularly bent sections 4, while the outer projecting ends of the bolts are removably engaged by nuts 15. It is apparent that the nut and bolt arrangements coöperate with the slotted attaching 15 plates for pivotally and slidably supporting the guard member and incidentally the slot serves to guide the sliding movement of these parts. In addition, by reason of the shoulders 14 the heads of the bolts 14' are 20 practically countersunk in the inner surface of the attaching plates whereby to facilitate an effective adjustment of the guard member.

In use, the guard member is normally arranged to rest upon the hearth in front of 25 the opening formed between the side columns and the hearth and lintel and thereby prevents pieces of burning or hot fuel from rolling from the hearth upon the adjacent floor. When it is not desired to employ the guard member it is only necessary to swing the same upwardly into close relation with the inner side faces of the columns and lift the guard upwardly where it 30 can be readily engaged on U-shaped support 15' the upper portion of which is provided with openings 16' adapted to receive fasteners (not shown) so as to be secured by such fasteners to the under surface of the lintel 35 of the fireplace. The lower portion of the support is arranged in closely spaced relation with the said under surface of the lintel so as to consequently support the outer portions of the angled sections in close relation to the under surface of the lintel as 40 indicated in Fig. 2.

In view of the foregoing description it is believed that a detail description of the operation is entirely unnecessary. Likewise it 50 is believed that the advantages of the invention will be readily apparent.

It will be understood that the foregoing description and accompanying drawings comprehend only the general and preferred 55 embodiment of this invention and that various minor changes in detail of construction, proportion, and arrangement of the parts may be made within the scope of the appended claims and without sacrificing any 60 of the advantages of this invention.

Having thus fully described this invention, what is claimed is:—

1. The combination with a fireplace, of a

guard including a U-shaped guard member, coöperative means for pivotally and slidably mounting the terminals of the guard member adjacent the opposed inner faces of the side columns of the fireplace to permit of the guard member being slid downwardly and swung outwardly so as to be arranged 70 in an extended position on the hearth of the fire place and also swung inwardly and slid upwardly so as to be arranged in close relation to the side columns and the lintel of the fireplace, and means for removably supporting the guard member in a raised position. 75

2. The combination with a fireplace, of a guard including a pair of slotted attaching plates, a substantially U-shaped guard member, means adjustably engageable with the terminals of the guard member and operably arranged in the slotted attaching plates for pivotally and slidably connecting the guard member to the slotted attaching plates, and a support connected to the lintel of the fireplace for removably receiving and supporting the guard member. 80

3. The combination with a fireplace, of a guard comprising a pair of attaching plates 90 having longitudinal slots therein, an anchoring portion formed on the lower end, the upper end of the attaching plates being provided with a slot, fastening devices engageable with the slots for anchoring the upper 95 ends of the plates to the side columns of the fireplace, a substantially U-shaped guard member, fasteners adjustably engageable with the terminal of the guard member, and slidably engaged in the longitudinal slots 100 for pivotally and slidably supporting the guard member, and a hook carried by the lintel of the fireplace for removably and slidably supporting the guard member. 105

4. The combination with a fireplace, of a guard therefor, comprising a pair of longitudinally slotted attaching plates anchored to the opposed inner faces of the side columns of the fireplace, a guard member embodying a pair of right angled sections, the outer ends of the sections being provided with a longitudinal series of openings, means for adjustably connecting the outer ends of the sections, the inner ends of the sections being also provided with a longitudinal series of openings, fastening devices engageable with any one of the openings in the inner ends and slidably engaged in the slotted attaching plates for pivotally and slidably connecting the guard member to the plates, and means carried by the lintel of the fireplace for removably supporting the guard member in a raised position. 115 120

In testimony whereof I affix my signature.

ERNEST T. HALEY.
